UNITED STATES PATENT OFFICE.

ROY CECIL MAJORS, OF RENO, NEVADA, ASSIGNOR TO STANDARD OIL COMPANY, OF SAN FRANCISCO, CALIFORNIA, A CORPORATION OF CALIFORNIA.

PET-COCK WRENCH.

Application filed July 20, 1925. Serial No. 44,817.

To all whom it may concern:

Be it known that I, ROY CECIL MAJORS, a citizen of the United States, residing at Reno, in the county of Washoe and State of Nevada, have invented a new and useful Pet-Cock Wrench, of which the following is a specification.

This invention relates to petcock wrenches and is more particularly directed to a pet-cock wrench for opening and closing oil gauge petcocks provided for determining the oil level in the crank case of a certain type of automobiles of very large manufacture. Heretofore, it has been customary, when serving this type of automobiles at service stations, to open and close the oil gauge petcocks by means of a wire rod having a pair of flat U shaped metal fingers rigidly attached to one end of said rod.

20 The disadvantages inherent in this former method and device is that occasionally an operator will forget to close the petcock with the result that the crank case oil will be completely drained from the crank case and 25 serious damage result to the engine.

It is, therefore, an object of this present invention to overcome this disadvantage by providing a petcock wrench that cannot be detached from the petcock until the said 30 petcock is in a closed position.

Other objects and advantages of this invention will be apparent from the following detailed description of a preferred embodiment thereof, as illustrated in the accompanying drawings.

In the drawings:

Fig. 1 is a perspective view of a petcock wrench embodying this invention.

Fig. 2 is a central sectional view thereof, 40 illustrating the wrench in position to be removed from the petcock, or to be connected therewith to open the same.

Fig. 3 is a similar sectional elevation illustrating the parts of the wrench turned to 45 position to open the petcock.

In the preferred embodiment of this invention shown in the accompanying drawings, 1 illustrates the body of the wrench to which a sleeve 2 is screw threaded as illustrated at 3 and which body 1 presents a forward extension 4 provided with a hook 5 which is adapted to fit over the end 6 of the petcock 7. A handle 8 passes through a guide sleeve 9 screw threaded to the sleeve 2 and through a bore 10 formed in the lower

end of the sleeve 2, and is secured to a pair of U-shaped fingers 11, as illustrated at 12.

The body 1 presents a circumferential shoulder 13 against which the upper edge 14 of the U-shaped fingers 11 rests when the handle 8 is rotated to the position illustrated in Fig. 3 so that it is impossible to remove the wrench from the petcock while the petcock is in the open position as is illustrated in Fig. 3.

60 The handle 15 of the petcock fits between the U-shaped fingers 11. A spring 16 is mounted upon the handle 8 between a washer 17 retained in position by means of a pin 18 passing through the handle 8 and the walls of the sleeve 2 around the bore 10, and is so mounted that when the wrench is rotated to the position illustrated in Fig. 3, the spring 16 is compressed and maintains the upper edge of the fingers 11 in engagement 65 with the circumferential shoulder 13 on the body 1.

70 The operation of this wrench is as follows:

The body 1 of the wrench is hooked over 75 the end 6 of the petcock and the handle 8 pressed forward until the U-shaped fingers 11 slip over the handle 15 of the petcock which can then be turned or opened to the position illustrated in Fig. 3. It will be 80 obvious from Fig. 3 that when the petcock is opened, the wrench cannot be removed, without rotation of the body 1, due to the fact that the upper edge of the U-shaped fingers having been rotated to approximately 90°, 85 cannot re-enter the housing provided in the body 1. When the petcock has been closed the spring 16 pulls the fingers 11 back into the non-operating position within the housing and the wrench can be removed simply 90 by lifting it off the petcock.

In Figure 1, 19 illustrates the transmission case of the said certain type of automobile. The petcocks are secured to the case in close proximity thereto. The hook 100 5 of the body 1 presents a flat edge shoulder 20 which engages the surface of the case 19 when the said hook 5 is engaged with the petcock preventing rotation of the body 1 of the wrench and therefore preventing withdrawal of the wrench until the fingers 11 are rotated to close the petcock.

105 Having fully described a preferred embodiment of this invention, it is to be understood that I do not wish to be limited to the 110

exact construction herein set forth which may, obviously, be varied in detail without departing from the spirit of the appended claims.

5 I claim:

1. In an article of the class described the combination with a body adapted to be engaged with a petcock, means rotatably mounted in the body and adapted to be engaged with the handle of the petcock to rotate the same to the open position, which means when operated to rotate the handle of the petcock to the open position prevents the removal of the wrench from the petcock 10 when the said body is held stationary.

2. An article of the class described comprising a body having a hook portion adapted to be engaged with a petcock, means rotatably mounted in the body and adapted to 20 be engaged with the handle of the petcock to rotate the same to an open position, which means comprise a pair of fingers which when rotated to an open position engage a portion of the body to prevent removal of the wrench 25 from the petcock when the said body is held stationary.

3. An article of the class described comprising a body adapted to be engaged with a petcock, means rotatably mounted in the 30 body and adapted to be engaged with the handle of the petcock to rotate the same, which means comprise a pair of fingers which when rotated engage a portion of the body to prevent the removal of the wrench 35 from the petcock, and means for yieldingly maintaining the said fingers in engagement

with the body when the fingers are rotated.

4. An article of the class described comprising a body, a pair of fingers rotatably mounted within the body, a handle secured 40 to the said fingers, a chamber formed in the body into which the fingers are yieldingly urged when in the non-operating position, and means for preventing the fingers from being urged into the recess when turned in 45 the body.

5. The combination with a case, having a petcock secured thereto, of a petcock wrench comprising a body adapted to be engaged with the said petcock, means rotatably 50 mounted in the body and adapted to be engaged with the handle of the petcock to rotate the same to an open position, and means on the body adapted to engage the case so as to prevent the removal of the said wrench 55 from the said petcock when the said petcock is open.

6. The combination with a case, having a petcock secured thereto, of a petcock wrench, having a body adapted to be engaged with 60 the said petcock, means rotatably mounted within the body and adapted to be engaged with the handle of the petcock to rotate the same to an open position, and an engaging shoulder formed on the body and adapted to engage the said case to prevent rotation of the said body when the same is engaged with the petcock.

Signed at Reno, Nevada, this 30 day of June, 1925.

ROY CECIL MAJORS.
